CIRCUIT INTERRUPTING DEVICE

Stanley T. Schofield, deceased, late of Wilkinsburg, Pa., by Martha M. Schofield, administratrix, Wilkinsburg, Pa., and James H. Frakes, Wilkinsburg, Pa., assignors to Westinghouse Electric & Manufacturing Company, East Pittsburgh, Pa., a corporation of Pennsylvania

Application February 20, 1937, Serial No. 126,890

12 Claims. (Cl. 200—146)

This invention relates to circuit interrupting devices and more particularly to load break disconnect switches. In the transmission of electrical energy over lines having moderate voltage and power requirements, the revenue which may be derived therefrom does not always warrant the cost of installing the customary switching equipment, such as disconnect switches and circuit breakers. It has been found that by providing a circuit interrupter which functions as a disconnect device and also as a load current interrupter, separate disconnect switches and circuit breakers may be eliminated thereby effecting a considerable saving in the cost of switching equipment.

Overload protection in conjunction with a circuit interrupter of the type to be hereinafter fully described may be obtained by the use of fuse devices which are relatively inexpensive to manufacture.

The main object of the invention is to provide a circuit interrupter capable of disconnecting the connected circuit under conditions of load from its source of supply.

Another object of the invention is to provide a load break disconnect switch in which the opening movement of the switch is utilized to actuate the contacts of an arc extinguishing structure for effecting load current interruption subsequent to the separation of the switch contacts.

A further and more specific object of the invention is to provide a load break disconnect switch in which the switch blade is connected at least during its opening movement with an arc extinguishing structure for causing current normally flowing through the switch to be transferred to the arc extinguishing circuit and in which the arc extinguishing contacts are actuated to the open circuit position by the further opening movement of the switch blade.

An ancillary object of the invention is to provide a load break disconnect switch of the type above described in which the final break during the opening operation takes place between the movable contact of the arc extinguishing device and a member carried by the switch blade, which member is adapted to be disengaged from the contact with a snap action.

Other objects and advantages relate to details of the switch structure and will appear more fully in the following description taken in connection with the accompanying drawings, in which

Figure 1 is a side elevational view of the switch-

ing device of the invention showing the circuit interrupting portion partially in section.

Fig. 2 is a sectional view of the device shown in Fig. 1, taken along the line II—II of that figure.

Fig. 3 is an enlarged side view showing the end portion of one of the switch blades and the attached interrupter actuating member in its normal position.

Fig. 4 is a sectional view taken along the line IV—IV of Fig. 5, showing the interrupter actuating member in a stressed position.

Fig. 5 is a plan view of the fragmentary switch blade portion shown in Fig. 4.

Fig. 6 is a vertical sectional view of the circuit interrupter portion of the switching device.

Fig. 7 is a cross sectional view taken along line VII—VII of the circuit interrupter shown in Fig. 6.

Fig. 8 is a cross sectional view taken along the line VIII—VIII of the circuit interrupter shown in Fig. 6, and

Fig. 9 is a cross sectional view taken along the line IX—IX of the circuit interrupter shown in Fig. 6.

Referring to the drawings, the reference numeral 10 designates a base upon which are mounted insulators 11, 13 and 15. Each of the insulators has a metallic cap portion 17 secured to the upper end thereof. A metallic terminal plate 18 interconnects the cap portion 17 of insulators 13 and 15. The insulator 13 is provided with a U-shaped bracket 19 to which is pivoted a forked member 21 by means of bolt 23. The forked member 21 carries a blade member 25, the free end of which is provided with a serrated contact portion 27 adapted to engage the toothed portion 29 of the U-shaped contact member 31 mounted upon the cap 17 of the insulator 11.

The bolt 23 pivotally supports one end of a pair of links 33, whereas the other ends of the links 33 are pivotally connected by means of a bolt 35 to a forked member 37 which, in turn, supports one end of a second blade member 39. The other end of the blade member 39 is provided with a contact portion 41 adapted to engage the side portion 43 of the contact member 31. The two contact portions 27 and 41 are coupled to each other by means of a pair of links 45. Due to the pivotal linkages 33 and 45, the blade member 39 is permitted to move longitudinally with respect to the blade 25.

It will be observed that as the blade 39 is moved to the right (Fig. 1), the coupling linkage 45 allows the contact portions 27 and 41 of the

blade members 25 and 39, respectively, to move toward each other, thereby releasing the high pressure engagement of these contact members with the fixed contact 31, which, in turn, permits 5 the entire blade assemblage to be swung upwardly about the pivotal pin 23 to an open position. During the closing operation of the switch blade assemblage, the blade member 39 is adapted to be moved to the left and in so doing is actuated 10 by the linkage 45 to cause the contact portions 27 and 41 to make a high pressure engagement with their respective cooperating contact portions 29 and 43 of the contact member 31. The cooperating contact portions 41 and 43 are smooth so as 15 to provide for a high pressure wiping engagement, whereas the contact portions 27 and 29 are toothed for the purpose of positively interlocking the insulator columns 11 and 13 when the switch is in the closed circuit position.

20 The switch assemblage is actuated to open and closed position by means of the insulator 15 which is provided with a shaft 47 journaled in a suitable bearing 49 mounted on the base 10. The upper portion of the rotatable insulator 25 15 is provided with an offset crank head 51 provided in this instance with crank pin bearings 53 and 55, respectively. The forked member 21 is provided with a short upstanding arm 57 which is coupled through a universal joint 30 58 to one end of an actuating rod 59, the other end of which is coupled by means of a universal joint 61 to the crank pin bearing 55. To the pivotal pin 35 is joined by means of a universal coupling 63 an actuating rod 65, the other end 35 of which connects with the crank pin bearing 53 through a universal coupling 67.

30 The crank pin bearing 55, as more clearly shown in Fig. 2, is slightly offset with respect to the center line joining the insulator columns 13 and 15 and has a lesser throw than the crank pin bearing 53, which is in alignment with the line joining the centers of the insulator columns 13 and 15 when the switch is in the normal or closed position. In opening the switch, the insulator column 15 is rotated counter-clockwise 40 as viewed in Fig. 2. It will be noted that during the initial rotative movement of the insulator 15, the crank pin bearing 53 in crank head 51 will cause the supporting links 33 to be rocked 45 about the pivotal pin 23 causing longitudinal movement of the switch blade 39 so as to release the high pressure engagement between the contact portions 27 and 41 and their cooperating contact members 29 and 43. Since crank pin 50 bearing 55 is positioned past dead center and has a lesser throw than the crank pin bearing 53, the former is permitted to travel through a considerable arc before imparting movement to the actuating rod 59, which subsequently 55 moves to the right as viewed in Fig. 1 and rocks the entire blade assemblage about the pivotal pin 23 to the open circuit position. It is thus seen that the relative positions of the crank pin 60 bearings 53 and 55 produce, in effect, a time 65 delay during the opening movement of the switch blade assemblage, which is sufficient to enable the high pressure contact to be broken prior to the actual movement of the blade assemblage to the open position.

70 In closing the switch blade assemblage, the reverse operations take place. It will be noted that the particular actuating linkage including the two operating rods 59 and 65 and their respective couplings to the crank head 51 maintain 75 the blade members 25 and 39 in the col-

lapsed position at all times during which the contact portions 27 and 41 are not in high pressure engagement with the fixed contact 31.

The contact 31 is provided with a terminal member 70 which carries conducting plate 71 bolted thereto or secured in any other suitable manner. The plate 71 serves as a support for an arc extinguishing device generally indicated at 73. The arc extinguishing device 73 comprises a cylindrical base 75 preferably of magnetic material, a metallic head portion 77 and an intermediate casing 79 of porcelain or other insulating material, which portions are adapted to be held in assembled relation with respect to each other by means of an insulating tie bolt 15 81, the upper end of which has threaded engagement with the head 77 and the lower portion of which extends through the conducting support plate 71 and is provided with a nut 83.

The base portion 75 and porcelain section 79 20 are lined with a cylindrical member 85 of insulating material. Within the lower portion of the cylindrical liner 85 is positioned a coil 87, one terminal of which is connected to the conducting support plate 71, and the other terminal 25 of which is connected to an annular contact plate 89. Within the coil 87 is disposed a tubular core 88 of magnetic material which extends upwardly slightly beyond the upper edge of the base 75. Immediately above the annular contact plate 89 is a cylindrical member 91 preferably of fiber or other suitable insulating material, which serves as the outer wall of an endless arc passage 93. The cylindrical member 91 also serves as a spacing member for supporting 30 an upper annular arcing plate 95 which is maintained in rigid engagement with the spacing member 91 by means of an annular insulating member 97.

The inner wall of the tubular arc passage 93 40 comprises a tubular lower section 99 of fiber or other insulating material and a tubular upper section consisting of a plurality of annular members 101 preferably of compressed boric acid or other suitable material which evolves large 45 quantities of arc extinguishing gas when acted upon by an arc. The upper and lower sections 99 and 101, respectively, are maintained in concentric relation about the tie bolt 81 and held in compression between the lower annular contact 50 member 89 and the upper annular arcing contact 95.

The arc passage 93 has an enlarged portion 103 as more clearly shown in Figs. 8 and 9 for the purpose of accommodating a movable contact member 105. Contact member 105 extends upwardly through a suitable aperture in the annular spacing member 97 and is provided with a series of insulating guide tubes 107, 108 and 109, which, in addition to giving the contact 60 member lateral support, also insulate it from the metallic head 77. The upper portion of the movable contact member 105 is provided with a hook or projection 111, the purpose of which will appear more fully hereinafter. 65

Immediately below the hook 111 is a hood 113 which is secured to the contact member 105 and movable therewith. The hood 113 extends downwardly over the opening in the tube 107 so as to prevent the entrance of ice and snow or 70 moisture into the arc chamber. A guide rod 115 is also provided having its lower end screw threaded into the head 77 and which extends upwardly through a suitable aperture in the upper wall of hood 113. The upper end of guide 75

rod 115 may be provided with nuts 117 which serve as stops to limit the upward movement of the movable contact member 105. The contact member 105 is biased to the circuit closing position by means of a coil tension spring 119 encircling the guide rod 115 and having its upper end anchored to the hood 113 at 121 and its lower end anchored to the head 77 at 123. One side of the hood 113 is provided with an inclined portion 125 which has an extension 127 extending downwardly and terminates adjacent the porcelain casing 79. The surface 125 is continued upwardly toward the hook 111 by means of a metallic filler member 129 thereby providing an elongated substantially flat contact surface, the purpose of which will be subsequently described.

To the inner face of contact member 27 of the blade 25 is secured a projecting arm 131. Pivoted to the end of arm 131 about a bolt 133 and sleeve 135 is a U-shaped bracket 137, which carries a curved contact actuating member 139, the free end of which is adapted to engage the inclined contact surfaces 125, 127 and 129. The actuating member 139 is biased to a normal angular position with respect to the arm 131 by means of a coiled spring 141 encircling the sleeve 135. The ends of the spring 141 terminate on opposite sides of the central portion of the bracket 137 and also upon opposite sides of a guide pin 143 secured to arm 131 and extending in parallel relation with the sleeve 135. The position of pin 143, as particularly shown in Fig. 3, determines the normal position of the actuating member 139 with respect to the arm 131 and the switch blade 25. It should also be observed that as the actuating member 139 is rotated either clockwise or counter-clockwise, as viewed in Fig. 3, such rotation will be against the bias of the spring 141. In the position shown in Fig. 1, the actuating member 139 is biased into contacting engagement with the contact surface 127 of the movable contact 105.

During the opening operation of the switch blade 25, actuating member 139 is maintained in contacting engagement with the surfaces 127, 125 and 129. As the upper end of actuating member 139 strikes the hook 111, further rotative movement of the switch blade 25 causes the movable contact member 105 to be moved to its full open position against the bias of spring 119. Upon further rotative movement of the switch blade 25 to the open circuit position, the actuating member 139 is rotated about its pivot at 133 against the bias of spring 141. In the dotted position shown at 145 in Fig. 1, the actuating member 139 is ready to disengage from the hook 111. Further rotative movement of the blade 25 will affect the disengagement, allowing the member 139 to be moved to its normal position as shown by the dotted lines at 147 in Fig. 1, which is substantially the full open position of the switch blade 25. Upon the release of the member 139 from the hook 111, contact 105 is quickly moved to the closed position by the action of spring 119. Thus, the contact portions of contact member and hook 111 separate under the biasing action of springs 119 and 141 which causes disengagement to take place with a snap action.

During the closing operation, actuating member 139 being biased to its normal position will strike the free end of hook 111 and upon further movement of the blade 25 toward the closed position will cause the member 139 to strike the

surface 125 with a hammer-like action, thus insuring a good contact between the member 139 and the surface 125 even though the latter be coated with sleet or ice. Likewise, the hammer-like action of the actuating member 139 during its upward movement in striking the hook 111 will insure a good contact between the member and the contact 105 during the opening movement of the switch.

The electrical circuit through the switch when it is in its normal or closed position is from the terminal 18, bracket 19, blades 25 and 39, contact 31, and terminal 70. A circuit also exists between the contact portion 27, arm 131, actuating member 139, contact surface 127, 125, contact 105, contact 89, coil 87, support plate 71 and terminal 70. However, since this latter circuit has a considerably higher resistance than that of the contact member 31, only a very small portion of the load current will flow through the interrupter circuit 73 when the switch blades 25 and 39 are in the closed circuit position. But, during the opening movement of the switch blades 25 and 39 after the latter have cleared the fixed contact 31, the current flow is from the terminal 18, bracket 19, switch blades 25 and 39, arm 131, actuating member 139, contact surface 125, movable contact 105, fixed contact 89, coil 87, support plate 71 and the other line terminal 70.

Upon the separation of contacts 105 and 89 by the upward movement of actuating member 139, an arc is drawn within the chamber 93. Current flowing through the coil 87 produces a radial magnetic field across the tubular arc passage 93 which forces the arc from the enlarged portion 103 of the passage into the constricted portion, thus causing the arc to intimately contact the walls thereof. The base 75 and the core 88 provide for the uniform distribution of magnetic flux across the arc passage 93. The action of the arc against the walls constituted by the fiber members 91 and 99 as well as the boric acid lining members 101, produces considerable quantities of arc extinguishing gas which are effective in aiding the extinction of the arc. As the arc is rotated in the slot-like passage 93, the ends thereof form terminals upon the fixed contact 89 and the upper annular arcing contact 95. The moving contact 105 moves upwardly beyond the upper contact plate 95, as indicated by the dotted position shown in Fig. 1, thus causing a second section of the arc to be formed between the arcing plate 95 and the lower end of the moving contact 105. This second section of the arc must exist in the narrow cylindrical passage 107 provided by the insulating tube 107. Inasmuch as the tube 107 provides the only means for venting the gaseous products of the arc from within the chamber 93, the arc within the tube 107 is thereby subjected to a longitudinal blast of arc extinguishing gas of considerable velocity. Thus, arc extinction is particularly effective due to the double action of the arc extinguishing gas upon two independent sections of the arc.

The arc extinguishing structure herein described is simple in construction, and due to its efficient arc extinguishing action may be so restricted in mass and external dimensions as to permit mounting thereof on the line terminal connection of a large variety of disconnect switches now in service. The simple but efficient actuating means employed for opening the circuit interrupter contacts render the problem of converting an existing switch into a load break disconnect device less difficult.

Although a particular load break disconnect switch combination has been shown and described, it is to be understood that the same is for the purpose of illustration and that changes and modifications may be made by those skilled in the art without departing from the spirit and scope of the appended claims.

It is claimed:

1. In a circuit interrupter, a pair of spaced conducting members, movable blade means for bridging said conducting members to establish an electrical circuit therebetween, means for moving said blade means into and out of engagement with at least one of said conducting members, an arc extinguishing device having separable contacts, one of which is connected to the said one of said conducting members, said separable contacts being in closed position when said blade means moves out of engagement with said one of said conducting members and means for releasably connecting said blade means in circuit with the other of said separable contacts to establish a second circuit between said conducting members and in parallel with the gap formed between said blade means and said one conducting member, said connecting means including means for actuating said separable contacts to open position to establish an arc therebetween following the disengagement of said blade means from the said one of said conducting members.
2. In a circuit interrupter, a pair of spaced conducting members, movable blade means for bridging said conducting members to establish an electrical circuit therebetween, means for moving said blade means into and out of engagement with at least one of said conducting members, an arc extinguishing device having a pair of separable contacts, one of which is connected to the said one of said conducting members, and means for releasably connecting said blade means with the other of said separable contacts to establish a second circuit between said conducting members, said connecting means being movable with said blade means and including means permitting said separable contacts to remain in engagement during the disengagement of said blade means from said one of said conducting members and movable to cause actuation of said separable contacts to open position and finally disconnecting from said other separable contact upon further movement of said blade means.
3. In a circuit interrupter, a pair of spaced conducting members, a movable blade member for bridging said conducting members to establish an electrical circuit therebetween, means for moving said blade member into and out of engagement with at least one of said conducting members, an arc extinguishing device having a pair of separable contacts, one of which is connected to the said one of said conducting members, and a connecting member pivotally mounted on the end of said blade member, said connecting member having limited sliding engagement with said other separable contact during the disengagement of said blade member from the said one of said conducting members and positive engagement with said separable contact following the disengagement of said blade member from the said one of said conducting members to cause a predetermined separation of said separable contacts upon further movement of said blade member, said connecting member being completely disconnected from said separable contact

upon final movement of said blade member to its open circuit position.

4. The combination with a switch having a contact, a blade and means for moving said blade into and out of contacting engagement with said contact of an arc extinguishing device having a fixed contact connected to said first contact, a cooperating contact member movable to open and closed positions, an actuating member pivotally mounted to one end of said blade, means biasing said actuating member into engagement with said contact member, said actuating member making sliding engagement with said contact member during the disengagement of said blade from said contact, means associated with said contact member for positively engaging said actuating member upon further movement of said blade to thereby cause separation of said fixed contact and said contact member, said contact member being disposed with respect to said actuating member to release the latter upon said contact member reaching its full open position, said biasing means being operative to cause the separation of said contact member and said actuating member with a snap action.

5. The combination with a switch having a contact, a blade and means for moving said blade into and out of contacting engagement with said contact of an arc extinguishing device having a fixed contact connected to said first contact, a cooperating contact member movable to open and closed positions, an actuating member pivotally mounted to one end of said blade, means biasing said actuating member into engagement with said contact member, said actuating member making sliding engagement with said contact member during the disengagement of said blade from said contact, means associated with said contact member for positively engaging said actuating member upon further movement of said blade to thereby cause separation of said fixed contact and said contact member, said contact member being disposed with respect to said actuating member to release the latter upon said contact member reaching its full open position, said biasing means being operative to cause the separation of said contact member and said actuating member with a snap action, and means for moving said contact member into engagement with said fixed contact upon the release of said actuating member.

6. A circuit interrupter comprising a fixed contact, a cooperating contact member movable to open and closed positions, a second fixed contact in circuit with said first contact, a blade member mounted for swinging movement into and out of engagement with said second contact, a conducting member pivoted to one end of said blade member, means biasing said conducting member to a predetermined position with respect to said blade member, said biasing means maintaining said conducting member in contact with said contact member during the disengagement of said blade member from said second contact and means associated with said contact member for positively engaging said conducting member for moving said contact member to open circuit position in response to further movement of said blade member towards its open circuit position, said biasing means cooperating with said engaging means to release said conducting member with a snap action when said contact member has reached full open position.

7. The combination with a switch having a contact and a blade member operable into and out

of engagement with said contact of an arc extinguishing device having an arc chamber, a fixed contact therein permanently connected to said switch contact, a cooperating movable contact member, means carried by said blade member and operable at least during the initial movement thereof to open circuit position for connecting said contact member in circuit with said blade member, said means being operative following the disengagement of said blade member from said switch contact to positively actuate said contact member to open position to thereby establish an arc within said arc chamber, said means being adapted to break the connection between said blade and contact members upon the latter member reaching its full open position, and means biasing said movable contact member towards said fixed contact for automatically returning said movable contact member to its closed position upon release of the connection between said blade and said movable contact member.

8. The combination with a switch having a contact and a blade member operable into and out of engagement with said contact of an arc extinguishing device having an arc chamber, a fixed contact therein permanently connected to said switch contact, the movable contact member having a portion normally within said arc chamber for cooperation with said fixed contact and a portion extending externally of said arc chamber, said exterior portion having an elongated contact surface and engageable means disposed adjacent said surface, means for normally biasing said contact member into engagement with said fixed contact, the conducting member carried by said blade member being adapted to slidably engage said contact surface to establish the circuit through said arc extinguishing device at least during the disengagement of said blade member from said switch contact, said connecting means being adapted to engage said engageable means following the separation of said blade member and said switch contact to actuate said contact member to the open circuit position against the action of said biasing means, said connecting means being adapted to release said contact member upon the latter member reaching its full open position as a result of further movement of said blade member to the open circuit position.

50 9. The combination with a switch having a contact and a blade member operable into and out of engagement with said contact of an arc extinguishing device having an arc chamber, a fixed contact therein permanently connected to said switch contact, a cooperating movable contact member, means carried by said blade member and operable at least during the initial movement thereof to open circuit position for connecting said contact member in circuit with said blade member, said means being operative following the disengagement of said blade member from said switch contact to actuate said contact member to open position to thereby establish an arc within said arc chamber, said means being adapted to break the connection between said blade and contact members upon the latter member reaching its full open position and means for returning said contact member into engagement with said fixed contact upon said blade reaching full open position.

70 10. The combination with a switch having a contact and a blade member operable into and out of engagement with said contact of an arc extinguishing device having an arc chamber, a fixed contact therein permanently connected to

said switch contact, a cooperating movable contact member, means biasing said movable contact member into engagement with said fixed contact, means carried by said blade member and operable at least during the initial movement thereof to open circuit position for connecting said contact member in circuit with said blade member, said means carried by said blade member being operative following the disengagement of said blade member from said switching contact to actuate said contact member to open position against the action of said biasing means to thereby establish an arc within said arc chamber, said biasing means assisting said means carried by said blade member to break the connection between said blade and contact members with a snap action.

11. In a circuit interrupter, a pair of spaced conducting members, movable blade means for bridging said conducting members to establish an electrical circuit therebetween, means for moving said blade means into and out of engagement with at least one of said conducting members, an arc extinguishing device mounted on said one of said conducting members and having separable contacts, one of which is connected to the said one of said conducting members, said separable contacts being in closed position when said blade means moves out of engagement with said one of said conducting members, and means for releasably connecting said blade means in circuit with the other of said separable contacts to establish a second circuit between said conducting members and in parallel with the gap formed between said blade means and said one conducting member, said connecting means including means for actuating said separable contacts to open position to establish an arc therebetween following the disengagement of said blade means from the said one of said conducting members, and said blade means moving to cause release of said releasable connecting means after causing actuation of said separable contacts to open position and then moving to a distance from said arc extinguishing device to establish an isolating gap capable of withstanding high voltage.

12. In a circuit interrupter, a pair of spaced conducting members, movable blade means for bringing said conducting members to establish an electrical circuit therebetween, means for moving said blade means into and out of engagement with at least one of said conducting members, an arc extinguishing device having therewithin a pair of arc establishing contacts, one of which is connected to the said one of said conducting members, and means for releasably connecting said blade means with the other of said arc establishing contacts to establish a second circuit between said conducting members, said connecting means including a part movable with said blade means and including means permitting said arc establishing contacts to remain in engagement during the disengagement of said blade means from said one of said conducting members and being movable to cause actuation of said arc establishing contacts to open position and finally disconnecting from said other arc establishing contact upon further movement of said blade means, and said blade means after disconnection from said other arc establishing contact moving to establish a wide gap in air from said arc extinguishing means.

MARTHA M. SCHOFIELD,
Administratrix of the Estate of Stanley T. Schofield, Deceased.

JAMES H. FRAKES.
